UNITED STATES PATENT OFFICE.

EMANUEL M. STERN, OF WALTON, NEW YORK.

CHARCOAL-STOVE.

SPECIFICATION forming part of Letters Patent No. 282,235, dated July 31, 1883.

Application filed April 5, 1883. (No model.)

To all whom it may concern:

Be it known that I, EMANUEL M. STERN, of Walton, in the county of Delaware and State of New York, have invented a new and Improved Charcoal-Stove, of which the following in a full, clear, and exact description.

The object of my invention is to provide a new and improved charcoal-stove of simple construction, which can easily and readily be connected with the stove-pipe of a heating or cooking stove, which charcoal-stove is especially adapted for heating smoothing-irons, shoe-makers' irons, book-binders' dies, &c., and for cooking, heating glue, and various other like purposes.

My invention relates to improvements in charcoal-stoves; and it consists in the peculiar construction and arrangement of the parts, as hereinafter more fully set forth, and pointed out in the claims.

Reference is to be had to the accompanying drawings, forming part of this specification, in which similar letters of reference indicate corresponding parts in all the figures.

Figure 1 is a perspective view of my improved charcoal-stove. Fig. 2 is a longitudinal sectional elevation of the same. Fig. 3 is a cross-sectional elevation of the same on the line *xx*, Fig. 2. Fig. 4 is a perspective view of the grated slide.

The stove-box A, made of sheet or cast iron, is provided on its upper edge with a flanged outwardly-projecting rim, B, adapted to receive the lower edge of a cover or hood, C, for retaining the heat, which cover is provided with a suitable handle, C', and directly below the rim a longitudinally-sliding plate, D, is held in the box A, which slide is provided with a series of openings, which can be closed by the usual stove-covers, E. The slide is provided at one end with a handle-ring, D'. In place of the sliding plate D a grated slide, F, can be used, and one can be replaced by the other. The slides rest on inwardly-projecting flanges *a*. A short distance above the floor or bottom of the box A a grate, G, rests on suitable inwardly-projecting flanges, *b*, or lugs. At the bottom of the front end the box is provided with a hinged or sliding door, H, having a draft-slide, H', of the usual construction. To the upper part of the rear end of the box A a piece of pipe, J, is attached, the free end of

which can be coupled to a pipe, K, secured to a curved plate or slide, L, which can be held on a stove-pipe, M, by two clips or grooved flanges, N, held on the stove-pipe parallel with the longitudinal axis of the same. The stove-pipe is provided with an opening between the clips or grooved flanges N. A slide, O, is provided for closing the opening in the stove-pipe when the charcoal-stove is not in use. The ends of the box A are supported by two platforms, P, each of which is supported by a pair of crossed legs, Q, which are provided with an eye or nut, R, at the crossing. A brace-rod or tie-rod, S, passing through the eyes or nuts, unites the two pairs of legs Q, and by means of the said rods and suitable nuts on the same the two pairs of legs can be adjusted and locked a greater or less distance from each other, according to the size of the box A.

The stove is set up and used as follows: The box A is placed on the platforms P, the legs of which have been adjusted the proper distance apart. The slide O is removed from the stove-pipe M and is replaced by the slide L, provided with the pipe K, whereupon the ends of the pipes J and K are coupled, so that the products of the charcoal on the bottom of the box can pass into the stove-pipe M. The smoothing-irons or other articles to be heated are placed on the slide D or F, and the cover C is placed on the box A. The gases cannot escape into the room, as they all pass through the pipes J K into the stove-pipe. No heat is lost, the articles are heated very rapidly, and the dust and dirt are prevented from spreading. The stove can be removed very easily and rapidly after use. My improved charcoal-stove can be connected with the pipe of any cooking or heating stove, and occupies very little space when not in use.

The stove can be placed on any other support different from the crossed legs shown.

If desired, the stove can be used without connecting it with a stove-pipe, the stove being placed in such a manner that the pipe J, or the pipe K, attached thereto, projects out of a window, and the smoke and gas can pass through the said pipes J K out of the room.

In practice I shall place a pan of any approved form below the lower grate to receive any falling ashes or embers.

Having thus described my invention, I claim

as new and desire to secure by Letters Patent—

1. The combination, with the stove-box A, provided with the internal flange, a, extending entirely around it, of the sliding top plate, D, provided with openings therein closed by covers E, and handle D', substantially as described and for the purpose set forth.

2. In a charcoal-stove, the combination, with the box A, having a flanged rim, B, of a sliding top plate for supporting the articles to be heated, and of the removable hood or top C, substantially as herein shown and described, and for the purpose set forth.

3. The combination, with the platforms P, 15 of the crossed legs Q, provided with the threaded eyes R, and screw-threaded connecting-rod S, passing through said eyes, substantially as described, whereby the legs can be adjusted to or from each other for different-sized stoves, as set forth.

EMANUEL M. STERN.
